A. J. ADAMS

FOOTREST FOR CHAIRS

Filed July 27, 1925

Patented Nov. 13, 1928.

1,691,036

UNITED STATES PATENT OFFICE.

ARTHUR J. ADAMS, OF BAY CITY, MICHIGAN, ASSIGNOR TO WILLIAM S. FERRIS,
TRADING AS DOMORE CHAIR COMPANY, OF ELKHART, INDIANA.

FOOTREST FOR CHAIRS.

Application filed July 27, 1925. Serial No. 46,230.

This invention relates to improvements in foot rests for chairs and it consists of the matters hereinafter described and more particularly pointed out in the appended 5 claims.

In relatively high chairs such as used by telephone operators, book keepers or others whose occupations call for the use of high desks or benches, members are provided on 10 said chairs for foot rests. However, such foot rests are usually fixed with respect to the standard or legs of the chair so that when the seat is adjusted with reference to the desk or bench, the foot rest is either too 15 high or too low for the occupant. If too high or too low, the lower limbs of the occupant become fatigued and achy due to either retarded circulation or cramped position of said limbs.

20 The primary object of the present invention is to provide a foot rest for such a chair which is readily adjusted with respect to the seat.

25 A further object of the invention is to provide a foot rest which may be readily adjusted by the occupant when sitting in the chair.

Still another object of the invention is to provide a foot rest frame which is pivotally connected at its rear end to the rear legs 30 of the chair and has an associated bail adapted to engage fixed parts of the chair to hold the front end of the foot rest frame with the foot rest member thereon in the 35 desired adjusted position.

These objects of the invention as well as others together with the many advantages thereof, will more fully appear as I proceed with my specification.

40 In the drawings:

Fig. 1 is a perspective view of a chair embodying one form of my improved foot rest.

45 Fig. 2 is also a perspective view of a chair embodying a modified form of my improved foot rest.

Fig. 3 is a horizontal sectional view through a chair embodying my invention, the plane of the section being taken on the 50 line 3-3 of Fig. 2.

Fig. 4 is a perspective view of the foot rest or board embodied in the construction shown in Fig. 2.

The invention is herein illustrated and 55 will be herein described as embodied in a

metallic chair but this is to be considered as by way of illustration only and not by way of limitation because as it will be apparent, the invention may also be embodied in other types of chairs where its peculiar 60 characteristics makes it advantageous to do so.

Referring now in detail to that embodiment of the invention illustrated in Fig. 1, the chair includes a rectangular seat frame 65 1 having front and rear members 2 and 3 respectively and side members 4-4 all made of vertically edgewise arranged strip metal. The front and rear members of said frame are bowed downwardly between their 70 ends as shown and supported on said frame is a seat 5. Said seat frame is mounted on pairs of front and rear legs 6 and 7 respectively, one at each corner of the seat frame and all made of tubular metallic 75 stock. Preferably the seat frame is vertically adjustable with respect to said legs and to this end I provide at each of the four corners of said frame, a stud 8 which fits snugly in the top end of associated leg and 80 is secured therein by a set screw 9.

The legs of the chair are of a greater height than in the ordinary chair and the legs of the front pair each include a long straight top portion 6^a and a forwardly offset bottom portion 6^b while the legs of the rear pair each include a long straight top portion 7^a and a rearwardly offset bottom portion 7^b, said offset portions increasing the spread of the legs in a manner providing 90 a more stable base or support for the chair as a whole.

The relatively long straight top ends of the legs are connected together by top and bottom sets of brace bars, each set including 95 side braces 10 and 10^a and front and rear bars 11 and 11^a respectively. The side brace bars of the top set of brace bars are provided with a plurality of longitudinally spaced upstanding studs or pins 12-12 as 100 shown. All the brace bars are made of tubular metallic stock and said studs or pins are preferably in the form of headed rivets fixed in the associated braces.

105 13-13 indicates side arms in the form of vertically edgewise disposed strap irons which are pivoted at their rear ends, one to each rear leg in the plane of the bottom set of brace bars. The front ends of said side arms extend a suitable distance forward of 110

the front legs and said ends are connected together by a foot rest member, 14 in the form of a tubular member. Said side arms may be swung about their pivotal connection with the rear legs into different angular positions as is apparent and associated therewith is an inverted U shaped bail 15. Said bail includes side members 16—16 the free bottom ends of which are pivotally connected to the side arms 13 near their forward ends, and a horizontal member, 17 which connects the top ends of the side members together and is adapted to engage upon the top brace bars 10—10 behind any one of the studs thereon and thus support the foot rest member in any one of its adjusted positions. Should it be desired to have a relatively high foot rest member, the member 17 of the bail will be engaged behind the rear most studs 12—12 and should it be desired to have a relatively low foot rest the member 17 will be engaged behind the foremost studs 12—12.

In Figs. 2, 3 and 4 I have illustrated a slightly modified form of the invention in that instead of using a relatively narrow bar-like foot rest member I make use of a wider foot rest member and the same is so arranged that no matter what height the same is adjusted to, it always is positioned in a horizontal plane.

As the chair itself including the legs and brace bars as the same as before described, they are indicated by the same reference numerals. In this instance there is provided at each side of the chairs a pair of arms each comprising parallel arm members 18 and 19 respectively which are pivoted at their rear ends to the rear legs 7—7. The front ends of said arms are bent downwardly and are pivoted to the end frame members 19 of a relatively wide foot rest member 20. The arms and foot rest provide a parallelogram so that no matter what elevation said foot rest member assumes, it will always remain horizontal. Preferably the foot rest member 20 is made of wood and the end frame members thereof include a horizontal bar 21 and vertical bar 22, depending therefore at the middle, the bottom end of said vertical bar being connected to the ends of the horizontal bar by angularly disposed braces 23—23, the front ends of the side arm members 18 and 19 being pivotally connected to said vertical bar as shown. To support the arm members in the desired adjusted position, I employ the same kind of a bail 15 as before described, the side members of which are pivotally connected to the side arm members 18—18 as shown.

My improved foot rest has many advantages: It may be readily adjusted by positioning the horizontal member of the bail 15 in back of the desired studs on the brace

bars and this adjustment may be made by the operator when occupying the chair if so desired. It does not require the use of tools of any kind and there are no parts to be removed with the usual probable loss thereof. While in describing my invention, I have referred to certain details of mechanical construction and arrangement of parts, I do not wish to be limited thereto except as may be pointed out in the appended claims.

I claim as my invention:

1. In combination with a chair having legs with pairs of braces connecting the same and a seat, arms pivoted to said legs, a foot rest member carried by said arms, and an inverted U-shaped bail operatively engaged at free ends with said arms and with its cross connecting member engaged on a pair of said leg braces for supporting the arms with the foot rest member in any one of several different positions.

2. In combination with a chair having legs and a seat and pairs of braces connecting said legs, arms pivoted to said legs, a foot rest member carried by said arms, and means operatively connected to said arms and adapted to engage at different points with one of said pairs of braces for a hanging support therefrom for supporting the arms with the foot rest member in any one of several different positions.

3. In combination with a chair having front and rear pairs of legs and a seat and braces connecting said legs, arms pivotally connected at their rear ends to said rear pair of legs and having their forward ends extending forwardly of said front pair of legs, a foot rest member carried on the forward ends of said arms, a bail pivoted to said arms and having a portion arranged above said braces, and means on said braces behind which the associated portion of the bail is adapted to be engaged to support said arms with the foot rest member in any one of several different positions.

4. In combination with a chair having front and rear pairs of legs and a seat and braces connecting said legs, arms pivotally connected at their rear ends to said rear pair of legs and having their forward ends extending forwardly of said front pair of legs, a foot rest member carried on the forward ends of said arms, a bail pivoted to said arms and having a portion arranged above said braces and longitudinally spaced studs on said braces behind which the associated portion of the bail is adapted to be engaged to support said arms with the foot rest member in any one of several different positions.

5. In combination with a chair having a seat and front and rear pairs of legs, a plurality of sets of braces connecting said legs together, longitudinally spaced studs

on one set of braces at the sides of the chair, a pair of arms pivoted at their rear ends to said rear legs and having forward portions extending beyond the front legs, and an inverted U shaped bail having side members pivoted to said arms and having a top member adapted to engage upon said one of said sets of braces at the side of the chair and behind the studs thereon to support the arms 10 with the foot rest member thereon in any one of several different positions.

6. In combination with a chair having a seat and front and rear pairs of legs, a relatively wide foot rest member at the front 15 of the chair, means providing parallelogram supporting members pivoted at one end to said rear legs and at its other end to said foot rest member, and means connected to said parallelogram means and adapted to be 20 engaged with fixed parts on said chair for holding said parallelogram means in the desired adjusted position, said means maintaining said foot rest member in any of its adjusted positions.

25 7. In combination with a chair having a

seat and front and rear pairs of legs, a relatively wide foot rest member at the forward end of the chair, means providing a parallelogram operatively connected at one end to said foot rest member and at its other end operatively connected to one of said pairs of legs, and means engaged with fixed parts of the chair and connected to said parallelogram means for holding the same in any one of several different positions.

8. In combination with a chair having a seat and front and rear pairs of legs, a relatively wide, horizontally disposed foot rest member at the front of the chair, means providing parallelogram supporting members, pivoted at their front ends to the foot rest member and at their rear ends to fixed parts of the chair, and means connecting said supporting members with other fixed parts of the chair for holding said supporting members and the associated foot rest member in the desired adjusted position.

In testimony whereof, I have hereunto set my hand, this 6th day of July, 1925.

ARTHUR J. ADAMS.
